UNITED STATES PATENT OFFICE.

FREDERICK B. CUMPSTON, OF BLOOMING GROVE, TEXAS.

COUPLING MEANS FOR DEMOUNTABLE-RIM SECTIONS.

1,241,345.

Specification of Letters Patent. Patented Sept. 25, 1917.

Application filed November 29, 1916. Serial No. 134,053.

To all whom it may concern:

Be it known that I, FREDERICK B. CUMPSTON, a citizen of the United States, and a resident of Blooming Grove, in the county of Navarro and State of Texas, have invented a certain new and useful Improvement in Coupling Means for Demountable-Rim Sections, of which the following is a specification.

10 One of the principal objects of my present invention is to provide an improved coupling means for circumferentially divided demountable rim sections, in the nature of a locking plate slidably carried on the under side of one of the sections, and having hooks adapted, when the sections are put together, to overhang a portion of the opposite section, and to be shifted for engagement with keeper lugs carried on the 15 under side of the opposite section.

Another object of the invention is to provide an improved device of the class described, which will be extremely simple, durable, efficient in operation, and inexpensive 20 to manufacture.

With these and other objects in view which will become apparent as the description proceeds, the invention resides in the construction, combination, and arrangement 25 of parts hereinafter more fully described and claimed, and illustrated in the accompanying drawing in which like characters of reference indicate like parts throughout the several figures, of which—

30 Figure 1 represents a view in section taken radially through a rim constructed according to my invention;

Fig. 2 represents a partial plan view showing the locking plate in position for coupling the rim sections together, the view being taken looking toward the under side of the rim;

Fig. 3 represents a view in perspective, showing the rim sections separated and illustrating the arrangement of the lugs carried by the rim sections;

Fig. 4 represents a view in perspective of the locking plate;

Fig. 5 represents an enlarged sectional view, taken transversely on the plane indicated by the line 5—5 of Fig. 2.

Referring more particularly to the drawing, a wheel felly is indicated at 5, and has the clincher rim mounted thereon. The 55 rim is divided circumferentially into a permanent section 6 which may be suitably se-

cured to the felly 5, and a removable section 7 which may be shifted laterally off of the felly and away from the section 6, in a manner well known, when it is desired 60 to remove the tire indicated at 8, or the inner tube thereof.

Secured on the under or inner face of the rim 7 along a line spaced from the inner edge 9 thereof, is a plurality of spaced lugs 65 10. These lugs are riveted or otherwise, suitably secured to the section 7, as indicated in Fig. 5. The lugs 10 serve as guide means for a locking plate, indicated generally at 11, which plate is adapted to bridge the joint 70 between the rim sections when the latter are placed together, and is adapted to be shifted longitudinally for engaging a plurality of spaced keeper lugs 12, welded or otherwise suitably secured on the under face of the 75 rim section 6, with hook portions 13 formed on said plate 11.

The plate 11 is provided adjacent one edge with a series of aligned longitudinally extending slots 14, corresponding in number 80 to the lugs 10 and through which slots said lugs extend. The lugs are provided with beveled lateral edges 15, and the lateral edges of the slots 14 are likewise beveled so that the plate will thus be retained in disengagement from the rim section 7. The slots 14 are substantially twice the length 85 of the lugs 10, whereby to allow a limited longitudinal movement of the plate 11 relatively to the rim section 7.

The hook portions 13 of the plate are defined by a series of L-shaped slots 16 provided in that portion of the plate which overhangs the rim section 6. The lateral reaches of the slots 16 extend clear to the 95 edge of the plate, so that the keeper lugs 12 may be introduced into the slots 16 when the section 7 is being placed in position upon the felly, it being understood that the laterally extending portions of the slots 16 are 100 spaced apart distances corresponding to the distances between the lugs 12. The keeper lugs 12 are beveled on all four edges, and all of the edges of the slots 16 are also beveled, so that the plate 11 will be held down 105 against the under surface of the permanent rim section 6 at all times that the lugs 12 are engaged within the slots 16.

It will be understood that, when the rim sections are to be connected together, the 110 plate 11 will be shifted to assume the dotted line position indicated in Fig. 2, and the

rim section 7 will be so positioned with respect to the section 6 that the bevel edged tongue 17, provided on the rim section 7, will be opposite the bevel edged recess 18 provided in a lug or thickened portion 19 of the rim section 6. The section 7 will then be moved against the section 6, so that the tongue 17 will enter the recess 18, and at the same time the lugs 12 will enter into the 10 lateral portions of the slots 16. When the sections are closed, the plate 11 will be shifted into the full line position indicated in Fig. 2, thereby engaging the lug 12 in the longitudinally extending portions of slots 16, 15 and hence engaging the hook portions 13 of the plate over the lugs in such manner as to prevent lateral displacement of the sections 6 and 7 relatively to each other.

The tongue 17 extends laterally beyond 20 the inner edge 9 of the section 7, and is tapered as shown, the recess 18 into which it extends being likewise tapered. This tongue, in engaging with the lug or thickened portion 19, prevents creeping movement of the 25 rim sections relatively to each other, and hence will prevent any possibility of disengaging the hooks 13 and lugs 12 through a creeping movement of the rim sections.

A plurality of the locking devices is 30 arranged at spaced intervals around the perimeter of the rim, and in order to accommodate the locking devices, the felly 5 is provided on its periphery with recesses 20 of suitable length to allow of the accommodation 35 of the locking devices and to allow the plates 11 to be shifted into and out of locking position. The recesses 20 are of sufficient depth to conveniently accommodate the locking devices, and in order to close these 40 recesses, the felly is provided with removable metallic lugs or blocks 21 removably held in position by means of bolts 22 which extend through the felly as indicated clearly in Fig. 1.

45 When the blocks 21 are in position for closing the recesses, they serve to support those portions of the removable section 7 which bridge the recesses 20, as clearly indicated in the drawing. When the rim sections 50 are to be disconnected, the blocks 21 are first removed, so that a suitable instrument

may be inserted in the recesses 20, for shifting the plates 11.

Although I have described the preferred embodiment of my invention, I may desire 55 to make such changes in the construction, combination, and arrangement of parts thereof, as do not depart from the spirit of the invention and the scope of the appended claims.

60 I claim:—

1. The combination with a circumferentially divided rim, of a plurality of bevel edged guide lugs carried on the under side of one of the rim sections, a securing device for the rim sections comprising a plate having bevel edged guide slots engaging the said guide lugs, said slots being of a length greater than the length of the guide lugs, said plate adapted when the sections are 70 placed together to overlie the opposite rim section on the under side thereof, a plurality of bevel edged keeper lugs carried by said opposite rim section on its under side, said plate being provided with bevel edged angular slots adapted to be engaged over the keeper lugs whereby to couple the rim sections together, and coacting means between the rim sections for guiding them together and for preventing creeping movement of 80 the sections relatively to each other.

2. The combination with a circumferentially divided rim, of a securing device for the rim sections comprising a plate adapted to bridge the joint between the rim sections when the latter are placed together, coöperating guide means between the plate and one of the rim sections for normally supporting the plate on said section and allowing longitudinal shifting movement of 85 the plate, a plurality of keeper lugs carried by the opposite rim section, a plurality of hook portions formed on the plate and adapted when the latter is moved in one direction to engage over the keeper lugs for 95 preventing separation of the rim sections, and coöperating guide means between the rim sections for properly guiding them together and for preventing creeping movement of one rim section relatively to the 100 other.

FREDERICK B. CUMPSTON.
